UNITED STATES PATENT OFFICE.

MILTON L. DODGE, OF NEWBURYPORT, MASSACHUSETTS.

METHOD OF MAKING TURN-SHOES.

1,241,939.

Specification of Letters Patent.

Patented Oct. 2, 1917.

Application filed November 6, 1916, Serial No. 129,660. Renewed August 30, 1917. Serial No. 188,878.

To all whom it may concern:

Be it known that I, MILTON L. DODGE, a citizen of the United States, residing at Newburyport, in the county of Essex and State of Massachusetts, have invented new and useful Improvements in Methods of Making Turn-Shoes, of which the following is a specification.

This invention relates to turn shoes and particularly to the method of fastening toe boxes therein.

In my copending application, Serial No. 110,855, filed July 24, 1916, I have disclosed a method of making a turn shoe with a previously molded stiff toe box, according to which the shoe is lasted, sewed, and turned without a toe box, after which the toe box is inserted into the shoe and secured by adhesive substance. A feature of the specificationally described method is that the toe portion of the lining is turned back until after the shoe has been turned and the toe box inserted, and is then tucked into the toe box. My present method is like that of the aforementioned application in that the toe portion of the lining may be turned back until after the shoe has been turned, and then tucked into the toe box; but the present method differs from my former method in that the toe box, which is previously molded, is attached to the shoe before the latter is turned. A new feature of the present invention is that the toe box is arranged right side up on the sole while the shoe is wrong side out, and is fastened directly to the sole or to the upper, as the case may be, before the shoe is turned, thus insuring suitable anchorage for the toe box to keep it in the desired position in the finished shoe.

Of the accompanying drawings:

Figure 1 represents a longitudinal vertical section through the toe portion of a lasted turn shoe before being turned right side out, and includes a toe box shown in its initial position by solid lines and in its ultimate position by dotted lines.

Fig. 2 represents a perspective view of a stiff molded toe box like that included in Fig. 1.

Fig. 3 represents a longitudinal vertical section of the toe portion of a lasted shoe similar to that shown in Fig. 1, the toe box being anchored directly to the sole by a tack instead of by the stitch shown in Fig. 1.

Fig. 4 represents a sectional view similar to Figs. 1 and 3 excepting that the toe box

is fastened directly to the pulled-over marginal portion of the upper instead of being fastened directly to the sole.

Fig. 5 represents a longitudinal vertical section through a shoe made in accordance with Fig. 1, the shoe being turned right side out and the toe portion of the lining being represented by solid lines in a turned-back position, and by dotted lines as having been tucked into the toe box.

Fig. 6 represents a vertical cross section through the shoe as shown by Fig. 5, in the plane indicated by line 6-6 of Fig. 5.

Fig. 7 represents a vertical cross section through the structure intersected by line 7-7 of Fig. 5.

The same reference characters indicate the same parts wherever they occur.

The toe portion of the last is indicated at 10, and the sole and upper are indicated respectively at 11 and 12. The pulled over marginal portion of the upper is secured to the sole by the usual stitches, one of which is indicated at 13, such stitches being arranged in the usual stitch-receiving channel 14 of the sole. The lining 15, with the exception of the toe portion thereof, is secured to the sole by the stitches 13 (see Fig. 6) but the toe portion 15' of the lining is initially turned back, as represented in Figs. 1, 3, 4 and 5.

Referring particularly to Fig. 1, a stiff molded toe-box like that shown by Fig. 2, is used. The body of the toe box is indicated at 16. It is provided with a flange 16' that is adapted to rest upon the sole. This flange is snipped at the toe end to provide a tab 17, and such tab is initially turned outwardly as shown by Fig. 2. The function of the tab is to receive the fastening means by which the toe box is to be secured directly to the sole. Still referring to Fig. 1,—the toe box is arranged, in the first instance, in the position represented by solid lines, and while in that position the tab 17 is secured by one or more stitches 18, after which the toe box is swung upwardly over upon the sole to the position represented by dotted lines. The initial position of the toe box is such as to leave ample space for the usual instrumentalities of a sewing or stitching machine to sew the stitches, and the toe box may therefore be secured by the stitches sewn by such machine. However, it would be possible to insert one or more additional stitches with

A hand needle to reinforce the connection between the tab 17 and the sole, and in such case the additional stitches would extend into the channel 11 in precisely the same relation as those sewn by the machine.

Although I have stated that the toe box is stiff, the term "stiff" is not synonymous with "rigid" or "brittle" for there is sufficient resistance and flexibility to enable the tab 17 to bend without cracking when the toe box is moved from its initial position to that indicated by dotted lines.

Instead of fastening the tab 17 by a stitch or stitcher as shown by Fig. 1, it may be fastened by one or more tacks 18 as represented in Fig. 3, and in such case the tack or tacks would be driven into the sole after the stitches 13 have been sewn. The toe box may, however, be secured directly to the pulled-over marginal portion of the upper instead of being secured directly to the sole, and Fig. 4 shows a stitch 19 extending through the toe portion of the toe box and through the pulled-over marginal portion of the upper. When this mode of fastening is employed the tab 17 may be cut off.

In each of the three examples illustrated and described the toe portion 15' of the lining is initially turned back as shown, so that the upper will lie in contact with the toe box when the shoe is turned. The turning operation may be performed as soon as the toe portion of the toe box has been secured by any of the methods described, and the toe box is held firmly in the desired position during the turning operation. After the shoe has been turned and stretched or otherwise smoothed to remove the wrinkles, the turned-back toe portion of the lining may be tucked into the toe box as represented by dotted lines in Fig. 5 and by solid lines in Fig. 7. In order, however, to keep the toe portion of the lining in such position, a suitable adhesive substance should be applied either to the inner surface of the toe box or to the contacting surface of the lining. If a slip-sole 20 (see dotted lines in Fig. 7) is to be used, its marginal portion would lie upon the flange 16' of the toe box.

If it is desired to fasten the rear portion of the toe box to the sole, the shoe may be placed upon a metal nailing-jack, and tacks 21 may be driven from the bottom of the

sole near the margin of the latter. The point of such tack would pass through the flange 16 of the toe box and on reaching the metal nailing jack would be turned back and elevated as shown by Fig. 8. The use of such tacks would be optional.

I claim:

1. In the art of making turn shoes, the method comprising the steps of lasting the upper and sole without a toe box, uniting the upper and sole, securing a stiff molded toe box directly to one of the lasted elements on the exterior of the lasted shoe, and turning the shoe, thereby inclosing the toe box.

2. In the art of making turn shoes, the method comprising the steps of lasting the upper and sole without a toe box, uniting the upper and sole, securing the toe end of a stiff molded toe box directly to one of the lasted elements in such relation as to enable the toe box to lie right side up on the ultimate inner face of the sole, and turning the shoe, thereby inclosing the toe box.

3. In the art of making turn shoes, the method comprising the steps of lasting the upper, a lining, and a sole, without a toe box, uniting the upper, the sole, and the lining, excepting the toe portion of the latter, leaving the said toe portion turned back from the toe end of the shoe, securing the toe end of a stiff molded toe box to one of the lasted elements in such relation as to enable the toe box to lie right side up on the ultimate inner face of the sole, turning the shoe, thereby inclosing the toe box, and tucking said turned-back portion of the lining into the toe box.

4. In the art of making a turn shoe, the method comprising the steps of lasting the upper and sole without a toe box, uniting the upper and sole, fastening a portion of a stiff molded toe box directly to one of the lasted elements, and then turning the shoe.

5. In the art of making a turn shoe, the method comprising the steps of lasting the upper and sole without a toe box, uniting the upper and sole, fastening a portion of a stiff molded toe box directly to the sole, and then turning the shoe.

In testimony whereof I have affixed my signature.

MILTON L. DODGE.
